9521

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 15,691, dated January 6, 1885.

Application filed November 22, 1884. Term of patent 3½ years.

To all whom it may concern:

Be it known that I, LOUISE TULLY, of the city, county, and State of New York, have invented and produced a new and original Design for a Pattern of a Lady's Basque, (numbered 9,521;) and I do hereby declare that the engraved prints accompanying this specification convey to any one accustomed to using paper patterns a clear understanding of how a garment made up by the pattern will appear.

The design shows closely-fitted fronts that shape a deep point at the end of the closing, a shorter point at each side, and a deep broad tab over each hip. A shorter closely-fitted back, the skirt of which exhibits under-

folded plaits extending from the waist-line of the middle three seams to the lower edge, flares from the fronts below the waist-line, and is straight across its lower edge, a standing collar, and coat-sleeves that exhibit a gathering and a high roll at the shoulder.

What I claim as my invention, and desire to secure by Letters Patent, is—

The design for a lady's basque, as shown in the engraved prints accompanying this specification.

LOUISE TULLY.
